UNITED STATES PATENT OFFICE

EARLE B. SMITH, OF ALHAMBRA, CALIFORNIA, ASSIGNOR TO GILLETTE SWEEPER CORPORATION, LTD., OF LOS ANGELES, CALIFORNIA, A CORPORATION OF NEVADA

COMB ATTACHMENT FOR CARPET SWEEPERS

Application filed July 13, 1931. Serial No. 550,304.

My invention relates to combs for cleaning the rotary brushes of carpet sweepers, and it has for a purpose the provision of a comb attachment which is mounted in relation to a brush as to be automatically operable to clean the brush when the latter is rotated in one direction and to cause the brush to clean the comb when the brush is rotated in the other direction, thus maintaining both the brush and comb thoroughly clean and free of all accumulations at all times.

It is also a purpose of my invention to provide in a carpet sweeper a duplex arrangement of combs as above described and wherein the two combs alternately function to clean the brush and then to be cleaned by the brush all according as the brush is rotated in one direction or the other the combs being pivoted at points above the brush axis and inclined upwardly so that when cleaning the brush they serve as gates between the dust pans and brush to conduct the dust and matter collected from the floor into the pans and thus prevent the matter from falling back on to the floor.

A further purpose of my invention is the provision of a comb mounting in which the comb tends to gravitate toward the brush so that when the brush is rotated in one direction, the comb reposes on the outer ends of the bristles to be cleaned by the latter, while when the brush is rotated in the other direction, the frictional engagement of the bristles with the comb teeth coupled with the tendency of the comb to move toward the brush, causes the comb to be automatically moved to a position in which its teeth are extended between the bristles thereby effecting cleaning of the latter.

I will describe only one form of comb attachment for carpet sweepers, embodying my invention, and will then point out the novel features thereof in claims.

In the accompanying drawing,

Fig. 1 is a top plan view of a carpet sweeper with the top thereof removed and having incorporated therein one form of comb attachment embodying my invention.

Fig. 2 is a transverse vertical sectional view taken on the line 2—2 of Fig. 1.

Figs. 3, 4, and 5 are semi-diagrammatic views showing the three positions which each comb is adapted to assume and in relation to the brush.

My invention in the specific embodiment herein illustrated is applied to a conventional form of carpet sweeper shown as including the usual body B mounted for rolling movement on wheels W and provided with a brush D which is rotatable about a fixed axis through the wheels and in either direction according as the body is moved in one direction or the other over a floor. Dust pans P are secured in the sweeper body at opposite sides of the brush to collect the dust and other matter removed from the floor by the brush.

The comb attachment embodying my invention comprises a pair of combs C and C' disposed at opposite sides of the brush D, and although they are reversely arranged, their specific construction and manner of mounting is identical, so that a description of one will suffice for both.

Each comb comprises an elongated body 15 preferably made of metal, and of concave-convex form in cross section to lend strength thereto. From one edge of the body 15, teeth 16 extend which are likewise formed of metal and cast or stamped from the same piece of metal as the body. The opposite ends of the body 15 are flattened and bent at right angles to form ears 17 which are provided with openings 18 in which pivot pins are received to support the comb as a whole for pivotal movement within the sweeper body B.

The pivot pins are indicated at 19, and, as shown in Fig. 2, they project inwardly from the end walls of the sweeper body B so as to support the comb C or C' for pivotal movement about an axis which is above the axis of rotation of the brush in order that the comb may function in a prescribed manner. Furthermore, the pivotal axis of the comb is offset or to one side of its longitudinal center or major axis of the comb so that when mounted on the pins 19 it constantly tends to gravitate toward the brush D to cause its

teeth to have cleaning engagement with the bristles of the brush.

To limit swinging or pivotal movement of the comb in either direction about the pins 19 as a center, I provide a pair of stop pins 20 which are secured in and project inwardly from the end walls of the sweeper body B at points above and slightly to the brush side of the pivot pins. These stop pins are relatively long, and their positioning is such that they are engaged by the ears 17 to limit swinging movement of the comb inwardly toward the brush D, and by the end teeth 16 to limit swinging movement of the comb outwardly away from the brush.

It is important to note that both the pivot pins and stop pins are formed of fiber or other non-metallic material in order to eliminate noise incident to the ears and teeth striking the stop pins and the comb swinging or being vibrated on the pivot pins.

During the normal reciprocating movements of the sweeper over a floor, the operation of the comb attachment is as follows:

With the brush D rotating in a counter clockwise direction as indicated by the arrow in Fig. 2, the right hand comb C occupies a stripping or cleaning position with respect to the brush, as shown in Figs. 2 and 3, and in which position the comb teeth pass between the brush bristles to remove therefrom all hairs, threads, dust, and other fibrous accumulations and to cause them to be deposited into the adjacent dust pan 35 therebeneath. This latter function is performed by reason of the position of the comb in respect to the brush and dust pan, as it will be clear that the comb acts as a chute to span the space between the pan and brush and to conduct the combings directly into the respective pan, rather than permit them to fall to the floor.

This stripping or cleaning position of the comb C' is defined by the respective ears 17 abutting the stop pins 20, and in such position the comb teeth are at an angle of substantially 45 degrees to and above a horizontal line intersecting the axis of the brush D. The comb is initially moved to this position by the combined action of gravity, due to the mounting of the comb, and the frictional engagement of the brush bristles with the comb teeth. The brush bristles in moving downward between the teeth actually pull the comb inwardly, and this action is positive and occurs immediately when the brush is rotated in a clockwise direction.

The other comb C, meanwhile, occupies a position tangent with respect to the periphery of the brush D so that the comb teeth repose on the outer ends of the brush bristles as best illustrated in Figs. 2 and 4, of the brush bristles. The comb C is moved to this tangent position by and concurrently with movement of the brush in a clockwise direc-

tion for the bristles then move upward against the comb teeth. At no time during the normal operation of the sweeper does the comb C move beyond this tangent position by reason of its natural tendency to gravitate toward the brush, and consequently, any combings remaining thereon are removed by the brush bristles passing upwardly of the comb teeth to effectively clean the comb. Thus it will be apparent that while the comb C' is functioning to clean the brush, the brush operates to clean the comb C.

So long as the brush D is rotated in a clockwise direction the two combs function as described, but when rotation of the brush is reversed, the combs instantly reverse their positions so that the comb C now operates to clean the brush while the brush operates to clean the comb C'. Thus it will manifest that according as the brush is rotated in one direction or the other, one comb cleans the brush and causes the resultant combings to be deposited into the respective dust pan, while the other is positioned to be cleaned by the brush. By reason of the mounting of the combs and their upward position in respect to the brush, the aforescribed mode of operation is entirely automatic and is accomplished without the use of springs.

Only when the sweeper is lifted from the floor and tilted or inverted, do the stop pins function to limit outward swinging movement of the combs, as illustrated in Fig. 5, and this is so done that once the sweeper is restored to a horizontal position the combs gravitate to a tangent position with respect to the periphery of the brush.

Although I have herein shown and described only one form of comb attachment for carpet sweepers therefor, each embodying my invention, it is to be understood that various changes and modifications may be made herein without departing from the spirit and scope of the appended claims.

What I claim is:

1. A sweeper comprising; a body; a brush rotatable in the body; a pan at one side of the brush; a comb movably mounted in the body at one side of the brush and above the pan and having its teeth projecting upward and towards the brush, and mounted so as to fall toward the brush with its teeth projecting into the brush, and means to limit movement of the teeth into the brush.

2. A carpet sweeper comprising; a body; a brush mounted in the body to rotate in either direction about a fixed axis; a pan beneath and at one side of the brush; a stripping comb in the body above the pan and at one side of the brush; coating means on the comb and body for supporting the comb so that its teeth extend upward and toward the brush and so that the comb is mounted for pivotal movement about an axis which is offset with respect to the

center of gravity thereof for swinging the comb teeth toward the brush; and means for limiting movement of the comb toward the brush so that when the brush is rotated in one direction the comb assumes a position with its teeth extended upward between the bristles of the brush to remove brush accumulations and guide the latter downward across the comb into the pan.

10 3. A carpet sweeper comprising; a body; a brush rotatable in the body; a comb at one side of the brush having ears; pivot pins in the body on which the ears are pivotally supported at one side of the center of gravity of the comb so that the comb tends to fall into the brush; and stop pins positioned in the body so as to engage the ears and thus limit movement of the comb toward the brush, said stop pins being of such length as to engage 15 the comb teeth and thus limit movement of the comb away from the brush.

20 4. A carpet sweeper comprising; a body; a brush mounted in the body to rotate in either direction about a fixed axis; a pan beneath and at one side of the brush; a stripping comb 25 in the body above the pan and at one side of the brush; coacting means on the comb and body for supporting the comb so that its teeth extend upward and toward the brush and so 30 that the comb is mounted for pivotal movement about an axis which is offset with respect to the center of gravity thereof for swinging the comb teeth toward the brush; and means for limiting movement of the comb toward 35 the brush so that when the brush is rotated in one direction the comb assumes a position with its teeth extended upward between the bristles of the brush to remove brush accumulations and guide the latter downward

40 across the comb into the pan; said last mentioned means being so correlated to the combs as to limit movement of the combs away from the brush whereby, when the sweeper is moved away from a horizontal position and then 45 returned, the combs will be restored to their normal operative positions.

EARLE R. SMITH.
